UNITED STATES PATENT OFFICE.

EUGENE VON VARGYAS, OF WASHINGTON, DISTRICT OF COLUMBIA.

DESIGN FOR A TREAD FOR AUTOMOBILE-TIRES.

50,881.

Specification for Design.

Patented June 5, 1917.

Application filed January 9, 1917. Serial No. 141,371. Term of patent 14 years.

To all whom it may concern:

Be it known that I, EUGENE VON VARGYAS, a subject of the Emperor of Austria, residing at Washington, in the District of Columbia, have invented a new, original, and ornamental Design for Treads for Automobile-Tires, of which the following is a specification, reference being had to the accompanying drawing, forming part thereof.

Figure 1 is a perspective view of part of a tire showing the design.

Fig. 2 is a face view of part of the tread of a tire showing the design.

I claim:

The ornamental design for the tread for automobile tires, as shown.

In testimony whereof I affix my signature.

EUGENE VON VARGYAS.
